Bell Aircraft Corporation, Buffalo, N. Y.

Application June 17, 1942, Serial No. 447,381

9 Claims. (Cl. 89—33)

This invention relates to gun installations, and more particularly to ammunition feeding means for use in conjunction with heavy caliber flexibly mounted firearms of the automatic or rapid fire types such as aerial cannon or the like.

One of the objects of the invention is to provide an improved means for feeding ammunition to a gun which is mounted at a position where only a small space is available for occupancy by the gun and the gunner so that the main ammunition storage magazine therefor must of necessity be located at a position remote from the gun. Another object is to provide an improved ammunition feeding mechanism whereby the firearm may be continuously fed with ammunition from a stationary magazine while the firearm is being moved through various angles of aiming adjustments. Another object of the invention is to provide an improved ammunition feed mechanism for the purposes above stated which is particularly adapted to accommodate the heavier caliber ammunition rounds such as are so large and heavy as to be difficult to feed satisfactorily in the form of linked ammunition belts. Another object is to provide an ammunition feed mechanism for the purpose described which comprises a dual element mechanism; one element of which comprises an ammunition feed magazine carried directly by the gun for immediate feeding of ammunition to the gun; and the second element of which comprises an automatically operating mechanism for replenishing the feed magazine automatically as the latter operates to charge the gun. Other objects and advantages of the invention will appear in the specification hereinafter.

In the drawings:

Fig. 1 is a fragmentary top plan of a combination ammunition storage and storage feeding mechanism of the invention mounted within a rotatable turret and in conjunction with an aerial cannon or the like, with portions of the storage feeding mechanism shown in section;

Fig. 2 is a fragmentary side elevation of the mechanism of Fig. 1;

Fig. 3 is a fragmentary end elevation thereof looking into the muzzle end of the gun;

Fig. 4 is a detail of the operating mechanism; and

Fig. 5 is a diagrammatic view of the cam control mechanism thereof.

In the drawings, the invention is illustrated in conjunction with an automatic firearm of the aerial cannon type which comprises generally a gun casing 10 and gun barrel 12. The gun is il-

lustrated as being mounted upon a rotating turret 14 by means of yoke arms 16—16 terminating in trunnions 18—18 whereby the firearm is rotatable about the horizontal trunnion axis for elevational aiming adjustments of the gun. It will be understood that rotation of the turret 14 about the vertical axis thereof will provide the necessary azimuth aiming adjustments of the gun, and that any suitable means for powering the elevational and azimuth adjustments of the mechanism may be employed. A crank arm 19 (Fig. 3) is keyed to the gun trunnion shaft for transmitting elevational adjusting movements to the gun from the control means therefor.

The ammunition feeding mechanism includes a small packet or gun feed magazine which is indicated generally at 20 as being mounted directly upon the gun casing and closely coupled thereto to move as a unit therewith in connection with all aiming adjustments of the gun relative to its support. The packet 20 comprises generally a closed circuit ammunition trackway which is approximately oval shaped in section and adapted to accommodate a series of ammunition rounds in side-by-side relation so as to be movable about the trackway toward a position of registry with the usual ammunition feedway port of the firearm. For this purpose the trackway structure comprises a cylindrical-like inner wall portion 22 which is flanked by outwardly extending flanges 24—24 at its opposite edges. Thus, the magazine 20 is of outwardly open continuous channel form and adapted to accommodate the ammunition rounds therewithin as indicated at 25 with the opposite ends of the rounds slidably abutting the corresponding flange portions 24—24 of the magazine. An endless conveyor for the ammunition rounds within the packet 20 is provided to comprise a series of plates 26 which are hingedly interconnected at corresponding end portions thereof by means of pins 27. A pair of opposed spring finger devices 28—28 extend from each of the plates 26 to resiliently engage upon the ammunition rounds 25 to resiliently clamp them in place upon the endless carrier. Cradles 29 also extend from the plates 26 to center the rounds and to cooperate with the spring fingers 28 to firmly hold the ammunition in place.

As illustrated in Fig. 3, the gun feed magazine trackway is interrupted at its lower section to engage upon opposite sides of the ammunition feedway portion 30 of the firearm; and it will be understood by those versed in the art that the customary feed pawl mechanism of the firearm will be adapted to engage the rounds of ammunition

which are loaded within the magazine 20 and to pull them successively into the breech mechanism of the firearm as required for the gun firing operation. Thus, in connection with each charging operation the feed pawl mechanism of the gun will operate upon the next-in-line ammunition round to pull the latter into position directly over the feed inlet port of the breech mechanism, whereby the entire length of the endless carrier will be motivated to shift around the wall portion 22 of the magazine whereby a new round of ammunition will be presented for the next following operation of the feed pawl mechanism. The movement of the ammunition carrier in this respect is in clockwise direction as viewed in Fig. 3, and a pair of rollers 32-32 are pivoted upon the magazine to engage at their peripheries against the plate members 26 of the carrier for easing the movement of the carrier around the bends of the magazine trackway.

Thus, it will be understood that the gun feed magazine 20 is mounted directly upon the gun and is arranged to continuously feed the ammunition feed pawl mechanism of the gun as long as the carrier of the packet magazine contains ammunition. However, due to limitations as to permissible size and capacity of the packet magazine, arrangement is made for continuously replenishing the carrier belt thereof as ammunition is withdrawn therefrom into the gun. For this purpose the invention embodies an automatically operating ammunition feed system which is adapted to withdraw ammunition from a main or storage ammunition magazine which may be located at any convenient position disposed remotely from the position of the gun. For example, as illustrated in Fig. 3 an endless type elevator as designated generally at 40 may be employed to elevate the ammunition into the approximate region of the gun from a storage compartment disposed at any convenient position therebelow, whereby the turret 14 housing the gun battery need be only of such size as to accommodate the gunner and the gun and the feed magazine 20 and the ammunition transfer mechanism of the invention. In such case the elevator 40 may comprise solely the primary ammunition magazine, or it may be arranged adjacent its lower end portion in registry with any suitable ammunition feeding mechanism whereby the elevator 40 will be continuously replenished with ammunition as it services the packet magazine 20.

In any case the elevator 40 is arranged to be power driven, and for this purpose the invention is illustrated herein as including an electric motor 42 coupled to a shaft 44 driving the sprocket engaging the lower end of the elevator chain 46. The elevator chain comprises a series of plates 48 which are linked together by means of pins 50 to provide a flexible endless link belt arrangement to train about sprockets 52-52 at the opposite ends of the elevator device. It will be understood that the lower elevator sprocket engages upon the motor drive shaft 44; and the upper elevator sprocket 52 is rotatably mounted upon a fixed cross shaft 54. A pair of spring fingers 56 extend from each of the elevator plates 48 to resiliently engage at opposite sides upon rounds of ammunition 25 when mounted therebetween, and cradles 58 are provided to center the ammunition rounds and to assist the spring fingers in holding the rounds against accidental disengagement from the elevator.

The plates 48 of the elevator 40 are each cen-

trally perforated as indicated at 60 for registry with spring-pressed pins 62 which are carried by the elevator sprocket 52 to extend radially therefrom at each plate engaging face portion thereof. The pins 62 are arranged to be normally urged by their spring mechanisms to extend outwardly of the sprocket 52 so as to register with and to be inserted through the apertures 60 of the corresponding elevator plate members as the elevator chain revolves about the sprocket 52; but the pins 62 are longitudinally dimensioned so that as the elevator plates 48 move into engagement with the sprocket 52 the ammunition round mounted upon each of the elevator plates forces the corresponding pin 62 to be moved inwardly against the action of its spring mechanism so as to extend at its opposite end into registry with a fixed stop device 64 which is carried by the stationary shaft 54. Thus, as the elevator operates to bring each successive ammunition round into a position of approximately horizontal alignment with the position of the upper sprocket shaft 54, the corresponding pin device 62 is pressed inwardly by the ammunition round thereof to engage the stop 64 for momentarily halting the elevator operation at this position. As soon as the ammunition round is removed from the elevator mechanism, as will be explained in detail hereinafter, the corresponding spring-pin device 62 will be thereby released and the engagement thereof against the stop pin 64 will be relinquished. Hence, the elevator mechanism will be free to operate again to rotate about the sprockets 52 to elevate the next succeeding ammunition round to the position of horizontal alignment with the feed-out position of the mechanism, whereupon the next succeeding spring-pin device of the sprocket will be depressed to engage the stop pin 64 for again interrupting the elevator operation until the next ammunition feed-out operation is effected, and so on.

To motivate the elevator mechanism, the motor 42 is coupled to the sprocket shaft 44 through means of a spring-coupling device. For this purpose a bell 70 is keyed to the sprocket shaft 44 by means of a pin 72, and a clock type spring 74 is arranged within the bell 70 so that the outer end of the spring 74 is fixed to the bell while the inner end of the spring 74 is fixed to the motor shaft 76. The shaft 76 is threaded at 78 to mount in screwthreaded relation thereon a control plate 80 which extends at an end portion 82 thereof into an axially slotted portion 84 of the bell 70. Thus, it will be understood that so long as the bell 70 and the motor shaft 76 rotate in unison the control plate 80 will remain stationary relative to the motor shaft. However, upon stoppage of the sprocket shaft 44, as by halting of the elevator operation by one of the spring pin devices as explained hereinabove, the bell 70 will be thereby retarded relative to the operation of the motor shaft 76 while the spring 74 absorbs the motion differential. Simultaneously, the control plate 80 will be thereby actuated to move axially of the motor shaft 76 toward the open end portion of the bell 70. A bell crank 86 is pivoted to the motor bracket at 87 and is arranged to be actuated by spring means to bear against the control plate 80 and to contact at its opposite end 70 portion the control element 88 of a switch 89 which is arranged to control the power supply circuit of the motor 42.

Thus, it will be understood that incidental to each elevator stopping operation the control plate 75 82 will be moved to actuate the motor switch 89

to open-circuit condition and that the spring 74 will be coincidentally stressed to absorb the shocks of the motion deceleration forces, and will be thereby tensioned in such manner as to provide an instantaneously available form of energy for re-starting the elevator operation. A ratchet pawl device as indicated at 90 (Fig. 1) is arranged to coact between the motor shaft and adjacent fixed structure to prevent unwinding of the spring 74 during periods of inactivity. Thus, upon subsequent release of the stop mechanism preparatory to recommencement of the ammunition feeding operation, the spring 74 will drive the elevator while the motor 42 is coming up to speed subsequent to re-closing of the control switch 89.

Upon such subsequent release of the elevator stop mechanism the bell 70 will be rotated under the action of the spring 74 relative to the shaft 76 whereupon the control plate 80 will be moved axially in reverse direction to release the bell crank 86 and the control finger of the electric switch 89, whereupon the motor 42 will be re-energized and will pick up the elevator driving operation as the pre-tensioned energy of the spring 74 becomes dissipated. Thus, an entirely automatic elevator driving operation is provided in combination with an elastic driving action whereby the upper sprocket 52 of the elevator may operate intermittently without imposing undue stresses upon the elevator driving mechanism; and whereby power for driving the elevator is instantaneously available at all times.

To transfer successive ammunition rounds from the upper end of the elevator 40 into the packet or gun feed magazine 20, a rotating carrier or transfer unit is provided as indicated generally at 91. The carrier comprises generally an arm 92 which is rotatably mounted upon a fixed housing 94 and bracket 95 by means of a tubular shaft 96 and spaced bearings 98-98 (Fig. 1). The axis of the shaft 96 is arranged to substantially coincide with the trunnion axis of the gun mount about which elevational aiming adjustments of the gun are effected. The shaft 96 is formed at an end portion thereof with an enlarged bell 100, and is arranged to be motivated by means of an electric motor and spring coupling and automatic motor control arrangement similar to the arrangement for motivating the elevator 40 as explained hereinabove.

Thus, the bell 100 is arranged to accommodate a clock spring 102 and the outer end of the clock spring is fixed to the bell 100 and the inner end of the spring is fixed to a motor shaft 104 extending from the armature of a motor which is indicated at 106. A control plate 108 is screw-threaded upon the motor shaft and arranged in splined relation with respect to the bell 100 as at 110. A spring pressed bell crank 112 is arranged to be actuated by the control plate 108 for pressing the control finger 114 of a switch 116 which controls the power supply circuit of the motor 106. Thus, the switch and actuating elements of the mechanism are so arranged that operation of the motor 106 will normally drive the shaft 96 to rotate the ammunition transfer arm 92 about an axis coincident with the elevational adjustment axis of the gun mount arrangement. However, upon stoppage of the transfer arm rotation, the coupling spring 102 will be stressed to accommodate the movement differential of the motor shaft 104 and the transfer arm, whereby the control plate 108 will be displaced axially of the motor shaft 104 to cause the bell crank 112 to open the motor control switch 116, thus deenergizing the 78

motor 106. A suitable ratchet device will be arranged in conjunction with the motor shaft 104 so that the energy so stored within the spring 102 will not be allowed to be dissipated by reverse operation of the mechanism; and thus, the spring will remain in a pre-tensioned condition whereby its energy will be available for driving the transfer arm 92 whenever it is subsequently released.

The transfer arm 92 embodies an ammunition carrier portion 120 which is adapted to register in ammunition receiving alignment with the feed-out position of the elevator mechanism 40 as explained hereinabove, and to be rotated by the arm 92 about the axis of the shaft 96 into ammunition discharge alignment with the ammunition intake portion of the packet magazine 20, irrespective of the position of the magazine 20 relative to the gun support base as will be controlled by the elevational angle of adjustment of the gun. Thus, as illustrated in Fig. 3, the transfer arm 92 is adapted to be rotated by the operation of the motor 106 so as to be first stopped at the position thereof illustrated in Fig. 3 wherein it is in ammunition receiving registry with the elevator segment which is in horizontal alignment with the elevator shaft 54, and then to be rotated and again stopped in alignment with the open left hand end portion of the packet magazine 20, and so on for continuous transfer of successive ammunition rounds from the elevator 40 into the gun feed magazine 20. Thus, the transfer arm 92 is adapted to alternately receive rounds of ammunition from the elevator 40 in the carrier portion 120 and to carry them to the position designated 125 for retransfer into the magazine 20; and for this purpose the feed-out portion of the elevator 40 and the intake port of the magazine 20 are so arranged as to be equidistant from the trunnion axis of the gun 10 so that irrespective of the angle of gun inclination for aiming purposes the transfer arm will be at all times adapted to register alternately with the feed-out portion of the elevator 40 and the feed-in portion of the magazine 20.

To effect displacement of ammunition rounds 45 from the feed-out portion of the elevator 40 into the transfer carrier 120, a lever bracket having a pair of parallel arms 126-126 is carried by a tubular shaft 128 which is in turn journaled upon a pair of bracket arms 130-130 extending from 50 the arm 92 so as to be integral therewith. Thus, the tube 128 is rotatably supported so that its rotation axis intersects at all times the axis of rotation of the transfer arm 92. The lever arms 126-126 are keyed to the tubular shaft 128 and 55 are interconnected by a cross bar 132. A coil spring 134 is arranged to substantially encompass the tube 128 and to be fixed at its opposite end portions to extending ears 136-136 of the bracket members 130-130. An intermediate body portion 60 of the spring 134 is arranged to extend as indicated at 138 (Fig. 2) into bearing relation against the cross bar 132, and the spring 134 is assembled upon the mechanism so as to be pre-tensioned in such manner as to at all times resiliently urge the 65 fingers 126-126 to rotate the tubular shaft 128 about its longitudinal axis in a counterclockwise direction as viewed in Fig. 3.

The free end portions of the fingers 126-126 are arranged so as to be adapted to engage behind successive rounds of ammunition 25 as they are lifted by the elevator 40 to the uppermost position thereof shown in Fig. 3; and thus it will be understood that the spring 134 tends to rotate the fingers 126-126 from the position thereof shown in Fig. 3 in counter-clockwise direction so as to press

the engaged ammunition round out of connection with the corresponding spring fingers 56 of the elevator 40 and into the transfer carrier 120 of the transfer unit 91.

To control the ammunition transfer operation of the fingers 126-126 the tubular shaft 128 is fitted with a cam arm 140 carrying a roller 142 which is adapted to track upon a circular cam portion 144 of the stationary bracket 94. As illustrated in Fig. 5 the cam surface 144 includes a raised portion and a dwell portion; and as shown in Fig. 3, the raised portion thereof is adapted to force the crank arm 140 to rotate the shaft 128 and fingers 126-126 against the action of the spring 134 into such position that the fingers 126-126 engage behind the ammunition rounds being elevated by the elevator 40. The recessed portion of the cam track 144 permits the arm 140 to retreat so as to allow the spring 134 to move the fingers 126-126 to kick the ammunition rounds out of the elevator fingers 56 and into the transfer arm carrier 120, and from thence into the ammunition inlet port of the feed magazine 20. For this purpose the fingers 126-126 extend through suitably apertured portions of the carrier 120 and into registry with the position of the ammunition round disposed therein, as indicated at 146 (Fig. 2).

To interrupt the ammunition transfer action of the fingers 126-126 at the stage where the round is disposed within the confines of the carrier 120 during the period that the transfer arm is rotating from the loading position thereof to the unloading position thereof, a second cam track portion 150 is arranged to extend from a circular plate 152 which is rotatably mounted upon the stationary bracket 94. The plate 152 is arranged so as to be rotatable about the axis of the shaft 96 while the cam track 150 is next adjacent to and inwardly concentric of the stationary cam track 144. The plate 152 is arranged to be rotatably shifted in unison with elevational adjustments of the gun 10 by means of a control arm 154 which extends rigidly from a bracket device 156 mounted upon the gun casing 10 at a position offset from the axis of elevational rotation of the gun.

Fig. 5 is a purely diagrammatic illustration of the cam track portions of the mechanism to show the operation thereof, and for the purposes of this illustration the cam tracks are shown as being lineally extended and relatively arranged approximately in accord with their functional relationships. It will be understood that the dimensioning and relative proportioning thereof will be regulated to suit different conditions of installations.

The cam track 150 is shown in the drawings as comprising a major body portion which is adapted to hold the roller 142 at an elevation approximately midway between the elevations of the high and low portions of the cam track 144; but in addition the cam track 150 is formed with a short dwell portion 160 which enables the roller 142 to drop to the elevation of the low portion of the cam track 144 at the time that the transfer carrier 120 reaches a position of ammunition unloading registry with respect to the ammunition intake portion of the feed magazine 20. Consequently, at this stage of operation of the mechanism the arm 140 is allowed to rotate further in counterclockwise direction as viewed in Fig. 3 under the impetus of the spring 134 whereby the ammunition transfer fingers 126-126 are enabled to move so as to push the engaged ammunition round from the carrier 120 into the am-

munition intake portion of the feed magazine 20.

To facilitate the two-stage ammunition transfer action into and then out of the transfer arm 120, the latter is fitted with a plurality of opposed spring rails 162 at positions above and below the engaged ammunition round, and the spring rail members are formed so as to be permanently set into such shapes as to have dwell portions intermediately of their ends for complementing engagement upon the ammunition rounds as the rounds are pressed laterally into the carrier 120. Thus, as the transfer fingers 126-126 press each successive round of ammunition into the carrier 120, the rounds initially deform the rails 162-162 elastically, and as the rounds then move into positions of registry with the dwell portions of the rails the latter close upon the rounds in resiliently gripping relation thereon and thus prevent the rounds from continuing to move through the carrier opening under the momentum forces thereof. However, upon subsequent operation of the cam controlled spring 134 to actuate the transfer fingers 126 in connection with their second stage of operation to move the rounds from the transfer carrier into the feed magazine, the rounds are pressed out of engagement with the rails 162 and are projected laterally from the transfer carrier into the feed magazine 20 as explained hereinabove.

To facilitate the loading of successive ammunition rounds from the discharge portion of the elevator 40 into the transfer carrier 120, it is arranged that rotation of the transfer unit about its axis of rotation shall be momentarily interrupted at each time for loading thereof. For this purpose a stop arm 164 is formed to extend fixedly from the shaft 128 so as to rotate therewith about the axis of the shaft 128 coincident with cam-controlled movements thereof. The stop arm 164 is so shaped as to side-pass the cam track 144 and to rotate with the transfer arm about the axis of the bearing 98 into the path of a stop abutment 166 which is fixedly mounted upon the stationary bracket 94. The stop 166 is formed with a sloping end face 168 (Fig. 4) and is so positioned circumferentially of the cam track 144 that as the arm control roller 142 comes into registry with the drop on the cam track 144 leading into the dwell portion thereof, the end of the stop arm 164 will abut against the sloping face 168 of the stop 166 to momentarily halt the rotation of the transfer arm unit. The slope of the face 168 is formed to be tangent to a radius extending therefrom to the axis of rotation of the shaft 128, and consequently, subsequent to the stop action referred to next above, the spring 134 will be enabled to rotate the unit comprising the shaft 128 and the cam arm 140 and the stop arm 164 in counterclockwise direction as viewed in Fig. 3, because the cam roller 142 will now be able to run down into the dwell portion of the cam track 144 while the stop arm 164 wipes out of engagement with the stop 166. Simultaneously, the ammunition transfer fingers 126-126 will be actuated to transfer a round of ammunition from the elevator into the carrier 120 as explained hereinabove; and thus upon completion of the disengagement of the stop devices 164-166 the transfer unit will be freed to continue to rotate in response to the action of the motor drive mechanism thereof toward a position of ammunition discharge registry with the ammunition intake portion of the feed magazine 20.

A second stop arm 170 (Fig. 2) is formed to ex-

tend rigidly from the shaft 128 and to side-pass the inner cam track structure 150 so as to rotate with the transfer unit as an integral part thereof into the path of a second fixed stop abutment 172 which is mounted to extend rigidly from the plate 152 which carries the cam track 150. The stop 172 is so positioned circumferentially of the cam track 150 as to be adapted to register with the stop arm 170 whenever the transfer carrier 120 reaches a position of ammunition discharge registry with respect to the ammunition intake portion of the feed magazine 20. It will be understood that since the plate 150 is automatically rotated about the elevational adjustment axis of the gun in response to all elevational adjustments thereof, the position of the stop 172 will be thereby automatically adjusted so that the stop 172 is adapted to function at all times to momentarily halt the rotation of the transfer arm unit whenever the latter moves into a position of ammunition discharge registry with the feed magazine 20, regardless of the elevational adjustment position of the gun.

The stop arm 170 and the stop abutment 172 are similar to the stop devices 164-166 referred to hereinabove, and thus it will be understood that they will be arranged to initially halt rotation of the transfer arm and then to permit the cam control shaft 128 to rotate to effect the second stage of ammunition transfer movement thereof from the transfer arm into the feed magazine 20; and that the parts are so proportioned and arranged that this last referred to operation will be effected by the force of the spring 128 in view of the fact that the cam roller 142 is at that time enabled to move into the dwell portion 160 of the cam track 150. Upon completion of the final ammunition transfer movement the stop devices 170-172 will be thereby disconnected, and the drive mechanism of the transfer arm unit will be thereby freed to recommence rotational movement of the transfer arm mechanism for return of the carrier portion 120 again into position for reloading; and it will be understood that this cycle of operation will thereupon be automatically repeated as long as the gun is fired.

In order to bolster the action of the spring 134 in connection with the ammunition transferring operations thereof, it is preferred to employ a supplementary spring and to arrange that the supplementary spring be automatically tensioned into increased activity as the spring 134 relaxes in conjunction with the untensioning operation thereof as is permitted by movement of the cam roller 142 into the dwell portions of the cam tracks 144-150. For this purpose a supplementary coil spring 180 is illustrated as connecting at one of its ends to a lug portion 182 extending from the tube shaft 128, and at its other end the spring 180 connects into one end of a shaft 184 which threads through the interior of the tube 128 and is arranged to be freely rotatable therewith.

At its opposite end the shaft 184 extends interiorly of the plan view position of the cam tracks 144-150 and is fitted at its inner extending end portion with a cam arm 186 carrying a roller 188 adapted to track upon a circular cam track 190 formed upon the plate 152 concentrically of the tracks 144-150. As illustrated in Fig. 5, the majority of the cam track 190 is of constant elevation but a rising abutment portion 192 thereof is disposed at such position thereon that whenever the cam roller 144 drops into the dwell portion 160 of the cam track 150 the cam

arm 186 is forced to rise and to rotate the shaft 184 in such manner as to tension the spring 180 in such direction as to cause the spring 180 to act upon the tube 128 to assist in the ammunition transfer operation thereof. Thus, it will be understood that whereas the primary spring 134 tends to relax and to exert a reduced pressure upon the ammunition transfer fingers 126-126 as the ammunition transfer operation proceeds, the supplementary spring 180 is automatically brought into play at such time to supplement the action of the spring 134 whereby a substantially uniform ammunition transfer action is obtained.

Thus, it will be understood that the invention provides a simple and rugged mechanism which automatically operates to maintain the immediate gun feed magazine in loaded condition by automatically transferring ammunition thereinto from a main storage magazine, and that the transfer mechanism of the invention is adapted to function uniformly and at constant speeds irrespective of the inclination of the gun and its feed magazine relative to the plane of the storage magazine.

The mechanism is adapted to start and stop automatically in accord with firing operations of the associated gun inasmuch as the operation of unloading the transfer carrier into the gun feed magazine is dependent upon the existence of ammunition receiving space within the magazine. This is because it is only upon movement of the ammunition carrier within the magazine 20 by the feed pawl mechanism of the gun to such a position that an empty ammunition receiving space moves into registry with the ammunition unloading position of the transfer arm, that it is possible for the transfer carrier to unload. Since continuance of the transfer arm rotational movement depends upon release of the stop devices 170-172 as controlled by the unloading action of the fingers 126-126 the movement of the ammunition carrier within the magazine 20 directly controls the ammunition transfer operation; and, as explained hereinabove, the automatic controls of the motors 42-106 function upon each complete stoppage of the ammunition transfer operation and upon each renewal thereof to alternately deenergize and energize the motors in accord with the ammunition feed requirements of the gun.

Thus it will be understood that the invention contemplates the provision of an ammunition feed magazine of compact form which is directly coupled to the gun and is operable thereby at all times in direct accord with the ammunition feed requirements thereof, and that the said feed magazine is of such capacity and size as to be enabled to respond readily to varying feed requirements of the gun and to operate with extreme flexibility in this respect. The feed magazine is arranged to be constantly replenished from the main storage magazine by means of a transfer mechanism which automatically starts and stops in accord with the ammunition requirements of the feed magazine; and the transfer mechanism is adapted to successively convey single rounds of ammunition from the storage magazine to the feed magazine with utmost facility irrespective of the angular adjustment of the feed magazine relative to the plane of the storage magazine as will be controlled by the aiming adjustments of the gun.

It will be understood that in lieu of the single transfer arm 92 illustrated and described hereinabove, any desired form of multiple arm ar-

angement may be employed and that in such case the additional transfer arms will extend radially from the common hub 96 and in spaced relation therearound; and that each transfer arm unit will embody a suitable ammunition carrier and displacement finger and cam controlled actuating shaft arrangement as illustrated and described hereinabove in connection with the transfer arm 92. It will also be understood that whereas the ammunition transfer mechanism of the invention has been illustrated and described hereinabove in detail only in connection with the transfer of ammunition from a storage magazine mounted stationarily with respect to the gun turret floor to a gun which is mounted to pivot about a horizontal axis for elevational aiming adjustments of the gun, that the invention is applicable with equal facility to the transfer of ammunition from a storage magazine disposed remotely with respect to a rotating gun mount table for transfer of ammunition to the gun battery irrespective of the azimuth adjustment thereof. It will also be appreciated that although only one form of the invention has been shown and described in detail to those skilled in the art the invention is not to be considered as so limited, but that various changes may be made therein without departing from the spirit of the invention or the scope of the appended claims.

I claim:

1. In combination, an ammunition feed mechanism and a gun mounted upon a support having a trunnion axis about which said gun is pivotable for aiming adjustments thereof, said gun having an ammunition feedway, said feed mechanism comprising an ammunition feed magazine mounted upon said gun in registry with said ammunition feedway and having an ammunition inlet portion thereof disposed eccentrically of said trunnion axis, ammunition storage means disposed remotely from the position of said gun and having an ammunition discharge portion thereof at a fixed position, the positions of said magazine ammunition inlet portion and said storage discharge portion being equidistant from said trunnion axis, and ammunition carrier means comprising a device mounted for rotation about said trunnion axis and including stop means operable automatically to alternately stop rotation of said carrier means at positions in registry with said storage discharge portion and with said magazine inlet portion irrespective of the angular aiming adjustment of said gun about said trunnion axis, and an ammunition transfer member rotatable with said carrier means and pivotable thereon, a first cam positionally regulated by the position of said ammunition discharge portion of said storage means, and a second cam positionally regulated by the position of said ammunition feed magazine inlet portion, said transfer member having a finger portion thereof adapted to bear against said first and said second cams to be cammed alternately thereby to pivotally actuate said transfer member so as to alternately displace successive ammunition rounds from said storage means into said carrier means and from said carrier means into said magazine, whereby to convey ammunition from said storage means to said magazine in accord with the feed requirements thereof.

2. In combination, an ammunition feed mechanism and a gun mounted upon a support having a trunnion axis about which said gun is pivotable for aiming adjustments thereof, said gun having an ammunition feedway, said feed mech-

anism comprising an ammunition feed magazine mounted upon said gun in registry with said ammunition feedway and having an ammunition inlet portion thereof disposed eccentrically of said trunnion axis, ammunition storage means disposed remotely from the position of said gun and having an ammunition discharge portion thereof at a fixed position, the positions of said magazine ammunition inlet portion and said storage discharge portion being equidistant from said trunnion axis, and ammunition carrier means comprising a device mounted for rotation about said trunnion axis and constructed and arranged to rotate to alternate positions in registry with said storage discharge portion and with said magazine inlet portion irrespective of the angular aiming adjustment of said gun about said trunnion axis, and an ammunition transfer member rotatable with said carrier means and pivotable thereon, a first cam positionally regulated by the position of said ammunition discharge portion of said storage means, and a second cam positionally regulated by the position of said ammunition feed magazine inlet portion, said transfer member having a finger portion thereof adapted to bear against said first and said second cams to be cammed alternately thereby to pivotally actuate said transfer member so as to alternately displace successive ammunition rounds from said storage means into said carrier means and from said carrier means into said magazine, whereby to convey ammunition from said storage means to said gun in accord with the feed requirements thereof.

3. In combination, an ammunition feed mechanism and a gun mounted upon a support having a trunnion axis about which said gun is pivotable for aiming adjustments thereof, said gun having an ammunition feedway disposed eccentrically of said trunnion axis, ammunition storage means disposed remotely from the position of said gun

and having an ammunition discharge portion thereof at a fixed position, the positions of said ammunition feedway and said storage discharge portion being equidistant from said trunnion axis, and ammunition transfer means having carrying means thereon adapted to pick up and convey ammunition rounds singly from said storage magazine discharge portion to said feed magazine inlet port, said pick up means comprising an ammunition carrier device rotatable between positions of registry with said magazine discharge portion and said feed magazine inlet port, said carrying device including a finger mechanism pivotable relative to said carrier and cam means connected to said finger mechanism and cam track means carried by said gun support in registry with said cam means and operable to actuate said finger means so as to project laterally from said carrier device as the latter is rotated into the region of said storage magazine discharge portion to engage behind ammunition rounds presented thereat and to thereupon initially move relative to said carrier to a limited extent so as to load said carrier with ammunition and then to move further as the carrier is rotated into registry with said feed magazine inlet port so as to unload the transferred ammunition from said carrier into said feed magazine.

5. In combination, an ammunition feed mechanism and a gun mounted upon a support having a trunnion axis about which said gun is pivotable for aiming adjustments thereof, said gun having an ammunition feedway disposed eccentrically of said trunnion axis, ammunition storage means disposed remotely from the position of said gun and having an ammunition discharge portion thereof at a fixed position, the positions of said ammunition feedway and said storage discharge portion being equidistant from said trunnion axis, and ammunition transfer means having carrying means thereon adapted to pick up and convey ammunition rounds singly from said storage magazine discharge portion to said feed magazine inlet port, said pick up means comprising an ammunition carrier device rotatable between positions of registry with said magazine discharge portion and said feed magazine inlet port, said carrying device including a finger mechanism pivotable relative to said carrier and cam means connected to said finger mechanism and cam track means carried by said gun support in registry with said cam means and operable to actuate said finger means so as to project laterally from said carrier device as the latter is rotated into the region of said storage magazine discharge portion to engage behind ammunition rounds presented thereat and to thereupon initially move relative to said carrier to a limited extent so as to load said carrier with ammunition, and second cam track means carried by said gun in registry with said cam means and rotatable with said gun about said first mentioned axis and adapted to cooperate with said cam means to actuate said finger means to secondarily move further relative to said carrier as said carrier moves into registry with said feed magazine inlet port so as to unload ammunition from said carrier into said feed magazine automatically irrespective of aiming rotational movements of said gun upon said support.

6. In combination, an ammunition feed mechanism and a gun mounted upon a support having a trunnion axis about which said gun is pivotable for aiming adjustments thereof, said gun having an ammunition feedway disposed eccentrically

of said trunnion axis, ammunition storage means disposed remotely from the position of said gun and having an ammunition discharge portion thereof at a fixed position, the positions of said ammunition feedway and said storage discharge portion being equidistant from said trunnion axis, and ammunition transfer means having carrying means thereon adapted to pick up and convey ammunition rounds singly from said storage magazine discharge portion to said feed magazine inlet port, said pick up means comprising an ammunition carrier device rotatable between positions of registry with said magazine discharge portion and said feed magazine inlet port, said carrying device including a finger mechanism pivotable relative to said carrier and cam means connected to said finger mechanism and cam track means carried by said gun support in registry with said cam means and operable to actuate said finger means so as to project laterally from said carrier device as the latter is rotated into the region of said storage magazine discharge portion to engage behind ammunition rounds presented thereat and to thereupon initially move relative to said carrier to a limited extent so as to load said carrier with ammunition, and second cam track means carried by said gun in registry with said cam means and rotatable with said gun about said first mentioned axis and adapted to cooperate with said cam means to actuate said finger means to secondarily move further relative to said carrier as said carrier moves into registry with said feed magazine inlet port so as to unload ammunition from said carrier into said feed magazine automatically irrespective of aiming rotational movements of said gun upon said support.

7. In combination, an ammunition feed mechanism and a gun mounted upon a support having a trunnion axis about which said gun is pivotable for aiming adjustments thereof, said gun having an ammunition feedway disposed eccentrically of said trunnion axis, ammunition storage means disposed remotely from the position of said gun and having an ammunition discharge portion thereof at a fixed position, the positions of said ammunition feedway and said storage discharge portion being equidistant from said trunnion axis, and ammunition transfer means having carrying means thereon adapted to pick up and convey ammunition rounds singly from said storage magazine discharge portion to said feed magazine inlet port, said pick up means comprising an ammunition carrier device rotatable between positions of registry with said magazine discharge portion and said feed magazine inlet port, said carrying device including a finger mechanism pivotable relative to said carrier and cam means connected to said finger mechanism and cam track means carried by said gun support in registry with said cam means and operable to actuate said finger means so as to project laterally from said carrier device as the latter is rotated into the region of said storage magazine discharge portion to engage behind ammunition rounds presented thereat and to thereupon initially move relative to said carrier to a limited extent so as to load said carrier with ammunition, and second cam track means carried by said gun in registry with said cam means and rotatable with said gun about said first mentioned axis and adapted to cooperate with said cam means to actuate said

finger means to secondarily move further relative to said carrier as said carrier moves into registry with said feed magazine inlet port so as to unload ammunition from said carrier into said feed magazine automatically irrespective of aiming rotational movements of said gun upon said support, said finger means comprising lever means and elastic means tending to bias said lever means toward ammunition unloading positions, and second elastic means arranged to supplement the action of said first elastic means upon dissipation of elastic energy thereof.

8. In combination, an ammunition feed mechanism and a gun mounted upon a support having a trunnion axis about which said gun is pivotable for aiming adjustments thereof, said gun having an ammunition feedway disposed eccentrically of said trunnion axis, ammunition storage means disposed remotely from the position of said gun and having an ammunition discharge portion thereof at a fixed position, the positions of said ammunition feedway and said storage discharge portion being equi-distant from said trunnion axis, and ammunition transfer means having carrying means thereon adapted to pick up and convey ammunition rounds singly from said storage magazine discharge portion to said feed magazine inlet port, said pick up means comprising an ammunition carrier device rotatable between positions of registry with said magazine discharge portion and said feed magazine inlet port, said carrying device including a finger mechanism pivotable relative to said carrier and cam means connected to said finger mechanism and cam track means carried by said gun support in registry with said cam means and operable to actuate said finger means so as to project laterally from said carrier device as the latter is rotated into the region of said storage magazine discharge portion to engage behind ammunition rounds presented thereat and to thereupon initially move relative to said carrier to a limited extent so as to load said carrier with ammunition, and second cam track means carried by said gun in registry with said cam means and rotatable with said gun about said first mentioned axis and adapted to cooperate with said cam means to actuate said finger means to secondarily move further relative to said carrier as said carrier moves into registry with said feed magazine inlet port so as to unload ammunition from said carrier into said feed magazine automatically irrespective of aiming rotational movements of said gun upon said

support, said finger means comprising lever means and elastic means tending to bias said lever means toward ammunition unloading positions, and second elastic means arranged to supplement the action of said first elastic means upon dissipation of elastic energy thereof and coupled to a third cam means carried by said gun for actuation of said second elastic means coincidentally with the cam controlled ammunition unloading operation of said finger means.

9. In combination, an ammunition feed mechanism and a gun mounted upon a support having a trunnion axis about which said gun is pivotable for aiming adjustments thereof, said gun having an ammunition feedway disposed eccentrically of said trunnion axis, ammunition storage means disposed remotely from the position of said gun and having an ammunition discharge portion thereof at a fixed position, the positions of said ammunition feedway and said storage discharge portion being equi-distant from said trunnion axis, and ammunition transfer means having carrying means thereon adapted to pick up and convey ammunition rounds single from said storage magazine discharge portion to said feed magazine inlet port, said pick up means comprising an ammunition carrier device rotatable between positions of registry with said magazine discharge portion and said feed magazine inlet port, said carrying device including a finger mechanism pivotable relative to said carrier and cam means connected to said finger mechanism and cam track means carried by said gun support in registry with said cam means and operable to actuate said finger means so as to project laterally from said carrier device as the latter is rotated into the region of said storage magazine discharge portion to engage behind ammunition rounds presented thereat and to thereupon initially move relative to said carrier to a limited extent so as to load said carrier with ammunition and then to move further as the carrier is rotated into registry with said feed magazine inlet port so as to unload the transferred ammunition from said carrier into said feed magazine, and stop means carried by said arm to register during rotation of said arm with abutment means for halting rotating movements of said arm as said carrier device registers alternately with said storage magazine discharge portion and said feed magazine inlet port.

JOHN C. TROTTER.
